DISPLAY DEVICE

Ralph J. Jorgenson and Foster L. Clute,
San Francisco, Calif.

Application September 23, 1941, Serial No. 411,986

4 Claims. (Cl. 40—125)

The present invention relates to improvements in a display device and it consists of the combinations, constructions and arrangements herein-after described and claimed.

A display device should be large in area in order to show an advertisement to the best advantage, and it should also be shallow in depth so as to occupy little window or floor space. Another qualification is that the device should be collapsible so as to be readily shipped. When using a large flexible sheet of material on which the advertisement appears, it is difficult to support the material in a vertical plane because the material is thin and flexible and therefore will readily buckle or fold. If the flexible material is applied to a corrugated cardboard backing, sufficient rigidity is provided to support it on a collapsible frame, but it is difficult to print on a sheet that has a corrugated cardboard backing.

The principal object of our invention is to provide a collapsible frame and a novel fastening and stretching means for securing a large flexible sheet of material to the frame. This permits the sheet to be printed and then applied to the frame. Although the frame is shallow in depth, it has sufficient supporting surface afforded by foldable feet to maintain the frame in a vertical position. The feet may be secured to a supporting surface by any suitable fastening means or by weights placed thereon.

If desired, two sheets of flexible material may be applied, one on each side of the frame, and the ends of the sheets may be secured to the frame in such a manner as to cause the sheets to be held smooth while in their supported state. Where both sides of the frame are covered with separate sheets of advertising matter, it is possible to support the frame from a ceiling rather than rest the frame on a floor or other supporting surface.

A further object of our invention is to provide a device of the type described which is simple in construction and durable and efficient for the purpose intended.

Other objects and advantages will appear in the following specification, and the novel features of the device will be particularly pointed out in the appended claims.

Our invention is illustrated in the accompanying drawing forming a part of this application, in which:

Figure 1 is an isometric view of one form of the display device and illustrates the device from the rear in order to set forth the frame construction more clearly;

Figure 2 is an isometric view of three of the frame members used in the form of the device depicted in Figure 1, these members being separated from each other for the purpose of clearly showing the slots;

Figure 3 is a perspective view of a modified form of the invention and shows the rear of the device to disclose the frame construction; and

Figure 4 is a plan view of a portion of another modified form of the invention.

While we have shown only the preferred forms of our invention, it should be understood that various changes or modifications may be made within the scope of the appended claims without departing from the spirit of the invention.

In carrying out our invention we provide a collapsible frame indicated generally at A. This frame may be made of any material desired and its members may be constructed in the shape of channels, angles or flat strips. In Figure 1, we show the members as being channel-shaped and constructed from corrugated cardboard; while in Figure 3, flat strips of corrugated cardboard are depicted. The corrugations in the cardboard are not indicated because of the smallness of the scale. We do not wish to be confined to any particular type of material, nor to any particular shape of material making up the frame members.

The frame A has a center vertical brace 1 which is channel-shaped. In actual practice the brace 1 is made from a sheet of laminated cardboard with two flat layers spaced from each other by a corrugated center section or layer. The sides 1a and 1b of the brace 1 are slotted adjacent to the top and bottom of the brace and we have illustrated in Figure 2 only the upper group of slots 2—2 and 3—3. Near the bottom of the brace we provide additional pairs of slots 4 and 5 similar to the slots 2 and 3. The web 6 of the brace terminates at the line 7, while the sides 1a and 1b are extended and are transversely scored at 8 and 9 for folding the extended portions 10 and 11 at right angles to form feet, see Figure 1.

The frame also consists of horizontal frame members 12 and 13, both of which are identical to each other, and therefore a description of one will suffice for both. A portion of the member 12 is illustrated in Figure 2 and it is provided with a pair of slots 14—14 in its sides 12a and 12b which are designed to cooperate with the slots 2 when the member 12 is secured to the brace 1. It will be noted that the slots 2 do not extend throughout the width of the side 1a nor do the slots 14 extend throughout the width of the sides 12 and 12b. The length of the slots 2 and

14 is such that their inner ends will abut each other when the edges 15 of the sides 12a and 12b lie flush with the outer surface of the web 6. Additional slots 16-16 are provided in the sides 12a and 12b and cooperate with the slots 3 for connecting the member 12 to the brace 1. In like manner the lower member 13 is secured to the brace 1, the slots 14 of the member 13 cooperating with the slots 4, and the slots 16 cooperating with the slots 5.

The member 12 has its web 17 lying flush with the edges 18 of the brace 1, and the web terminates at the ends 19-19. The sides 12a and 12b extend a slight distance beyond the ends 19 of the web and are curved in the manner shown at 20. The member 13 is similarly constructed and corresponding reference numerals are applied.

We provide a flexible sheet of material indicated generally at B which may be paper, cloth, or any other material desired. The width of this material is preferably equal to the length of the web 6, while the length of the material is in excess of the lengths of the members 12 and 13. The ends 21 and 22 of the material are secured to reinforcing and stiffening strips 23 and 24 of corrugated cardboard or any other reinforcing material desired. Both ends 21 and 22 of the flexible material are slotted in the same manner to be received in slots provided in the members 12 and 13, and therefore a description of one cooperating group of slots will suffice for all groups, and corresponding reference numerals will be applied to all groups. In Figure 2, the end 22 is illustrated and this end is slotted at 25 to receive the side 12a of the member 12. The side 12a has a cooperating slot 26 therein, and the web 17 has a slot 27 for receiving the portion 22a of the end 22. The side 12b is not slotted and therefore a long slot 28 is die-cut into the end 22 to receive the side 12b. The lower end of the portion 22 is provided with similar slots in order that this portion may be secured to the member 13 in like manner.

The slot 26 is positioned at a distance from the curved edges 20 of the member 12 which will cause the flexible sheet B to extend around the curved edges 20 and be likewise curved. When the end 22 and the reinforcing strip 24 are forced into the slots 26 and 27, they will create a tension on the flexible material to hold it tightly in place and the material will be stretched around the edges 20. The opposite end 21 is secured to the members 12 and 13 in like manner and a further description need not be given. It will be noted that the reinforcing members 23 and 24 extend beyond the lower edges of the ends 21 and 22 and are bent to form feet 29 and 30. The web 6 may be fastened to the flexible material B by glue, paste, cement, or any other cementitious material, or it may not be secured to the flexible member. We have found the best results to be achieved when the web 6 is fastened to the flexible material B at its center, and this will permit the ends of the material to be secured to the members 12 and 13 in the manner already indicated. The fastening of the web 6 to the material B prevents the top and lower edges 31 and 32 of the material from curling.

The feet 10, 11, 19 and 30 will support the frame in an upright position and may be secured to a supporting surface by suitable fastening means, or weights may be placed on the feet. The width of the feet causes them to lie within the depth of the frame A. The curved edges 20 of the horizontal members 12 and 13 cause the ma-

terial B to curve in a like manner, and this will give the proper rigidity to the material B so that it can stand on edge. At the same time a finished effect is afforded to the device when the edges are curved rearwardly in the manner shown.

It is possible to use angle braces or flat braces rather than channel members or box like members. In Figure 3, we illustrate horizontal flat bracing members cooperating with a center vertically disposed angle brace 33. The frame C shown in this figure has its flexible material D secured to a side 33a of the vertical brace 33. The vertical brace has its other side 33b extending at right angles to the side 33a and provided with a slot 34 near each end for receiving horizontal members or braces 35 and 36. The horizontal braces have slots 37 for receiving the unslotted portions of the side 33b and have recesses 38 for receiving the side 33a. This will cause the edges 39 of the braces 35 and 36 to lie flush with the outer surface of the side 33a and therefore to contact with the back of the flexible material D.

It will be noted that the recess 38 is twice as long as the width of the side 33a and this will permit the braces 35 and 36 to be turned end for end and applied to the brace 33 without interfering with the proper assembly of the frame C. In other words, the brace 35, for example, can be attached to the brace 33 with the curved ends 40 arranged in one position or with the ends oppositely positioned. Cooperating slots 41 and 42 in the horizontal braces 35 and 36, and the ends 43 of the flexible material D respectively are provided for permitting the ends to be secured to the braces in much the same manner as the ends of the form of the device shown in Figure 1 are secured to their braces. Reinforcing members 44 are fastened to the ends 43 and are also received in the slots to act as wedges for holding the flexible material in a stretched condition. The ends 43 may be moved further into the slots to take up any stretching of the paper D. The side 33b has an extended portion 45 bent at right angles to form a foot, and each reinforcing member 44 has an extended portion 46 also bent at right angles to form a foot. The feet support the frame and the flexible material in the same way as that set forth in the other form of the invention. The feet extend lengthwise of the frame and permit a shallow frame being used.

It is possible to dismantle both forms of the device, shown in Figures 1 and 3, quickly, and the horizontal bracing can be folded into lengths less than their overall lengths if the channels or angles are longer than the height of the flexible material. For example, the horizontal channel 12 can first be opened out flat and then bent along a scoring line 47. This will permit the horizontal members to be considerably longer than the height of the flexible material, and still the overall length of the package when the parts are collapsed need not exceed the height of the flexible material. The flexible material is rolled into a compact cylinder when the device is dismantled for shipping purposes.

In Figure 4, we show still another modified form of the invention where the horizontal members 48 may be channel-shaped with upper and lower sides 48a that have double curved ends 49 and 49'. In place of the cooperating slots 25 to 28 inclusive, the end 50 of the flexible material E carries a button 51 to which a string 52 is secured. The free end of the string is wrapped

around a second button 53 that is secured to the side 48a. The string may be tightened about the button 53 for stretching the material E taut about one of the curved ends 49 of the member 48. A central vertical member 55, similar to the member 1 is connected to the two horizontal channels 48 in the same manner as the member 1 is connected to the members 12 and 13. Only one central vertical member need be used.

It is possible to cause the frame to support a sign on both sides, and a second sheet of flexible material E' representing the second sign is shown mounted in place. The sides 48a of the channel have a second curved portion 49', and a slot 54 separates the curved portions 49 and 49' from each other. The ends 50 and 50' of the two sheets E and E' are received in the slot, and the buttons 51 and 51' have strings 52 and 52' secured thereto. The string 52' may be wound around the same button 53. The strings hold the paper taut about the channels and are hidden from view by the two pieces of flexible material E and E'. If the buttons 51 and 51' adjacent to the upper horizontal member 48 are placed below the member, the string will rest on the member 48 and will have a tendency to stretch the sheets E and E' upwardly. The reverse can take place at the lower horizontal member 48 by placing the buttons 51 and 51' above this member and causing the string to pass below the side 48a and thus pull downwardly on the lower portions of the sheets E and E'. This will stretch the sheets tight by pulling up at the top and down at the bottom of both sheets adjacent to their ends.

The advantages of the display device are several. It permits a display of any soft, flexible material and holds it in a smooth flat plane. The material may stand on its edge or be supported from above. The display may be used in a small space because the device is shallow. This is ideal for show windows where it is desired to place objects in front of the device. The device will stand erect even though of shallow depth and this is made possible by the feet which extend in the direction of the length of the device. The feet are no wider than the depth of the device and may be secured to the supporting surface by fastening means or weights. The device is fool-proof in the way it can be assembled. Assembling can be quickly and accurately accomplished. The display device is light in weight even though it covers a large vertical area when assembled. This reduces the cost for shipping. The device is also compact when disassembled for shipping or storing. The demountable frame when assembled permits the stretching of any flexible material thereover and the material may carry an advertisement if desired.

The paper or flexible material B and D need not be provided with slots 25, 28 and 42 before the material is secured to the frames A or C since the cutting can be done by a knife or other in-

strument at the time of assembly. This will save an expensive die cutting job for the paper or other flexible material.

We claim:

- 5 1. In combination, a frame including a central member, a flexible sheet secured to the member, other members removably secured to the central member and having rounded ends, said sheet overlying the other members and having portions extending around the rounded ends, said second-named members having slots therein for removably receiving the ends of the sheet, and reinforcing and sheet stiffening members paralleling the sheet ends and being receivable in the slots for wedging the sheet ends in the slot.
- 10 2. In a display device, a flexible sheet, a frame including an angle member having one side permanently secured to the sheet, the other side being swingable from a plane paralleling the sheet plane into one extending at right angles thereto, frame members removably secured to the angle member so as to extend at right angles thereto and having rounded ends, the sheet contacting with the frame members and having its greater portion lying in a flat plane with the sheet ends extending around the rounded frame member ends, and means for removably securing the sheet ends to the frame members.
- 15 3. In a display device, a flexible sheet, a frame including an angle member having one side secured to the sheet, the other side being swingable from a plane paralleling the sheet plane into one extending at right angles thereto, frame members removably secured to the angle member and having rounded ends, the sheet contacting with the frame members and having its greater portion lying in a flat plane with the sheet ends extending around the rounded frame member ends, and means for removably securing the sheet ends to the frame members.
- 20 4. In a display device, a flexible sheet, a frame including an angle member having one side secured to the sheet, the other side being swingable from a plane paralleling the sheet plane into one extending at right angles thereto, frame members removably secured to the angle member so as to extend at right angles thereto and having rounded ends, the sheet contacting with the frame members and having its greater portion lying in a flat plane with the sheet ends extending around the rounded frame member ends, and means for removably securing the sheet ends to the frame members, reinforcing members secured to the sheet ends and having foot portions for supporting the frame and sheet, said foot portions lying inside of planes paralleling the front and back of the frame.
- 25 5. A display device comprising a frame made up of at least two parallel members with slots adjacent to their ends, a transverse member secured to the parallel members, and a piece of flexible material having advertising thereon and extending over one side of the three members, the ends of the material extending around the ends of the parallel members and being frictionally held in the slots for holding the material taut, reinforcing strips secured to the ends of the material and being received in the slots, the reinforcing strips constituting supporting frame legs and having feet whose planes extend at an angle to the plane of the material for supporting the display device in an upright position.
